UNITED STATES PATENT OFFICE

136,754

DESIGN FOR A MASK FOR TYPEWRITING MACHINES

Lewis Cary Myers, Freeport, N. Y., assignor to Royal Typewriter Company, Inc., New York, N. Y., a corporation of New York

Application October 4, 1943, Serial No. 111,262

Term of patent 14 years

To all whom it may concern:

Be it known that I, Lewis Cary Myers, a citizen of the United States, residing at Freeport, in the county of Nassau and State of New York, have invented a new, original, and ornamental Design for a Mask for Typewriting Machines, of which the following is a specification, reference being had to the accompanying drawings, forming part thereof.

I claim:

The ornamental design for a mask for typewriting machines, as shown.

LEWIS CARY MYERS.
